Patented Nov. 21, 1922.

2 SHEETS—SHEET 1.

A schematic diagram of a beam structure. It consists of a horizontal top chord and a vertical bottom chord. A horizontal member, representing a support, connects the two chords at the center. Two vertical lines, representing loads, are attached to the bottom chord at the left and right ends of the beam.

UNITED STATES PATENT OFFICE.

GILBERT G. ROSINO, OF SANDUSKY, OHIO.

FOOT-IMPRESSION-TAKING DEVICE.

Application filed February 9, 1918, Serial No. 216,414. Renewed August 21, 1922. Serial No. 583,427.

To all whom it may concern:

Be it known that I, GILBERT G. ROSINO, a citizen of the United States, residing at Sandusky, in the county of Erie and State of Ohio, have invented certain new and useful Improvements in Foot-Impression-Taking Devices, of which the following is a specification.

This invention embodies a device for taking foot impressions of the class presented in Letters Patent No. 1,225,500 granted to me May 8th, 1917. The essential purpose of the invention is to provide a simple means whereby impressions of a foot or like part may be readily made upon a sheet of paper or similar material, the impression thus made affording a record of the size and configuration of the foot or equivalent member, and additionally providing a record of any abnormalities of the part the impression of which is taken.

In the improvements hereof I utilize an endless belt type of inking member instead of the winding and unwinding type of my patent above identified and I provide also some other details of construction with regard to the inking instrumentalities as well as a novel arrangement of the impression sheet and supporting means therefor, together with means for facilitating the removal and replacement of the endless inking member.

For a full understanding of the present invention, reference is to be had to the following description and the accompanying drawing in which:

Figure 1 is a perspective view of a device embodying the invention;

Figure 2 is a longitudinal sectional view approximately on the line 2—2 of Figure 1;

Figure 3 is a bottom plan view of the removable inking and paper holding unit; and

Figure 4 is a cross section on the line 4—4 of Figure 2.

Throughout the following detail description, and on the several figures of the drawing, similar parts are referred to by like reference characters.

The present invention in its preferred embodiment comprises a receptacle 1 of somewhat box-like form, the same increasing in depth so to speak from one end to the other. The receptacle comprises the sides 1^a and 1^b, and the ends 2 and 3; also the bottom 4. For reasons which will be obvious herein-

after the bottom 4 might readily be dispensed with if desired. In the box 1 is arranged the endless inking member 5 preferably made of rubber and passing around the rollers 6 and 7, the roller 6 being disposed beneath a cross piece 8 and the roller 7 beneath a cross piece 9 notched at 9' as seen in Figure 1. The rollers 6 and 7 are journaled in side plates, a pair of which are designated 10 and the other pair of which are designated 11, these plates being attached to opposite edges of a rigid support 12 about which the inking member 5 travels. The support 12 is really a board to the under side of which are secured U-shaped plates 13 the ends of which constitute legs 13 resting upon the bottom 4 of the box 1 and rigidly holding the support 12 in place and disposed within the box. A U-shaped plate 14 is secured to the under side of the support 12 and an inking roller 15 is journaled in the depending ends of said plate 14 and so disposed that it is adapted to operate in contact with the endless inking member 5 to supply ink to the inner surface of said member.

The rollers 6 and 7 have a surface adapted to distribute the ink supplied to the member 5 by the inking roller 15, and said rollers are so arranged that they support the member 5 spaced from the support 12 but adapted to be depressed by the foot when placed thereon and moved downwards. This action results from the inherent elasticity of the inking member 5 which, as stated before, is made of rubber or like substance.

As shown best in Figure 3, one of the journals of the roller 6 is extended to form a crank handle 16 by which the roller may be turned whereby to move the endless inking member 5 longitudinally of the support 12 for purposes of re-inking the same, in an obvious manner. Plates 11 are formed with approximately rectangular extensions 11^a one of which terminates in an arm 11^b and another in an arm 11^c, the arm 11^c having an opening to receive one end of a removable pintle 17 and the arm 11^b having a notch 18 for the same purpose. The sheet upon which impressions may be made by means of the inking member 5 is 105 preferably rolled and may be printed with dimension figures or otherwise, not shown, it being common to use such printed sheets in connection with foot impression taking operations. The roll of the paper is desig-

nated at 19 and the paper as it is unrolled from the roll passes over the support 12 as seen in Figures 2 and 4 of the drawings and issues from the box 1 through a long slot 20 in the side 1^a. The side 1^a is notched out at 21 to facilitate grasping of the edge of the paper sheet to pull the same across the support 12.

As seen in the drawings, the paper for the roll 19 when manipulated to pass over the support 12 rests upon said support and is maintained spaced from the under inked side of the inking member 5. It is therefore necessary that the portion of the inking member 5 above the sheet upon which the impression is to be made shall be depressed to establish contact between said sheet and the inking member to apply the inked impression to the sheet. I provide on the upper surface of the supporting member a covering 12^a. I have used billiard cloth as the preferable covering material.

It is notable that the inking instrumentalities and the impression sheet supply or feeding instrumentalities are assembled in one unit on and about the support 12 and may be bodily removed therefrom, these parts being illustrated as when removed, in Figure 3. Should it be required to remove and replace the inking member 5 the cross piece 8 may be moved pivotally in the manner shown in Figure 3 to disconnect one end thereof from the adjacent side plate 10. When so moved the member 5 is detachable by slipping the same off the support 12 edgewise of the latter in an obvious manner. For the above purpose the cross piece 8 is pivoted at 22 to an integral bent-over extension 23 of the adjacent rectangular extension 11^a of the adjacent plate 11. A fastening member 24 is carried by the other end of the cross piece 8 and is adapted to interlockingly engage in a notch 25 of the adjacent plate 10. To facilitate the removal of the inking and paper holding unit the end of the side 1^a near the crank handle 16 is notched out at 26.

When an impression has been taken in the self-evident manner of use of my invention, the portion of the roll of paper 19 beneath the inking member 5 may be readily pulled outwards until the entire impression-holding portion of the sheet has passed through the slot 20 of the box 1. Thereafter the sheet may be pulled outwards to tear the same off for use and to establish the desired record.

In renewing the roll of paper 19 the inking and paper holding unit will preferably be slightly raised at the end supporting the cross piece 8. The pindle rod 17 is then lifted at one end from the notch 18, carried laterally, and pulled endwise to disengage it from the opening of the arm 11^a. The

roll may then be placed upon the pindle rod and the latter replaced in its operative position.

The plates 10 and the plates 11 with the frame-like extensions 11^a form centering means within the box 1 of the removable unit comprising the base 12, the inking member 5 and the roll holder 17 and specific directly connected and associated parts. It is noted that the receptacle or box 1 is broadly a holder for said unit and a feature of the invention consists in the arrangement of the inking device 15 so that it will supply sufficient ink to the member 5 for operative impressions, as an incident to relative movement of the parts 15 and 5, the base 12 being always rigid and non-yielding so as to insure clearness of the impression taking action.

Having thus described my invention, what I claim as new is:

1. In a foot impression taking device, the combination of a receptacle, and a removable inking and paper holding unit disposed therein and embodying a base, a roll paper holder mounted on said base, and a movable inking member extending over the base in spaced relation thereto, the paper roll holding member being arranged so that the paper may pass therefrom between the inking member and the base transversely respecting movement of the inking member.

2. In a foot impression taking device, the combination of a receptacle and foot impression means disposed therein and comprising a removable unit embodying a base, an inking member adapted to travel over said base longitudinally of the holder, and a roll paper holder between one side of the said support and one side of the receptacle, and disposed longitudinally of the holder, the opposite side of the receptacle having a slot through which paper from said holder may pass.

3. In a foot impression taking device, the combination of a receptacle, and a removable inking and paper-holding unit disposed therein and embodying a base, a roll-paper-holder mounted on said base, an inking member extending over the base in spaced relation thereto, the paper-roll-holding member being arranged so that the paper may pass therefrom between the inking member and the base, connections between the roll-paper-holder and the said support permitting the ready detachment of said holder, a cross piece spanning said support and extending over said inking member, and means movably supporting said cross piece whereby it may be moved to a position facilitating removal of the inking member from the support.

4. In a foot impression taking device, the combination of a holder, an inking unit disposed therein and comprising a base, an

- endless inking member passing around said base, an inking device on said base operating in contact with the inner surface of the inking member and adapted to supply said 5 surface with a sufficient amount of ink for operative purposes as an incident to the movement of the inking member relatively to the base, and means to support said base in a rigid non-yielding manner relatively 10 to the holder and spaced from the base so that the base remains stationary during the inking action of said inking device.
5. In a foot impression taking device, the combination of a holder, an inking unit disposed therein and comprising a base, an endless inking member passing around said base and spaced therefrom, an inking device on said base operating in contact with the inner surface of the inking member and 15 adapted to supply said surface with a sufficient amount of ink for operative purposes as an incident to the movement of the inking member relatively to the base, means to support said base in a rigid non-yielding 20
- manner relatively to the holder and spaced from the base, so that the base remains stationary during the inking action of said inking device, the inking device consisting of an inking roller beneath the support and between said support and the inking member. 25
6. A foot impression device comprising a base having supporting means therefor to maintain the base in a rigid, non-yielding position, an endless inking member passing about said base, means for causing movement of said member, an inking device between the inking member and the base and adapted to supply sufficient ink to the inking member during its movement to establish operative impressions, the inking member operating in spaced relation to the base whereby a sheet of material may be introduced between the base and the inking member and remain spaced from the latter preliminary to an impression operation. 30
- In testimony whereof I affix my signature. 35
